GUIDO FORNACA, OF TURIN, ITALY, ASSIGNOR TO F. I. A. T., A CORPORATION OF NEW YORK.

COMBUSTION-ENGINE.

1,193,004.

Specification of Letters Patent.

Patented Aug. 1, 1916.

Application filed January 5, 1911. Serial No. 600,855.

To all whom it may concern:

Be it known that I, Guido Fornaca, a subject of the King of Italy, residing at Turin, Italy, have invented certain new and useful Improvements in Combustion-Engines, of which the following is a full, clear, and exact specification.

This invention relates to combustion engines, more particularly those used for motor vehicles, and has for its object to provide a cast block multiple cylinder engine in which the carbureter casing will be an integral part disposed adjacent the cylinders and within the water jacket.

As now generally constructed, the carbureter is made separably from the engine and attached thereto, and in some instances external pipes are connected from the water jacket through the casing of the carbureter, so that the casing will be in a measure heated by the water jacket. This involves extra work, and also external pipe fittings, which are objectionable because of the added complication, and also detract from the appearance of the engine. Also, such heating arrangements are not fully effective and do not always heat the charge to the most efficient temperature.

According to this invention, the air which is to form the combustible charge is caused to pass in contact with surfaces heated by the water jacket and forming a part thereof into a space preferably formed between two of the cylinders in a block casting, in which space the fuel nozzle will also be disposed so that not only will the air be heated, but the charge will be continuously heated during its entire passage to the cylinders. Thereby, the carbureter is placed as close as possible to the inlet valves and a more efficient distribution of the combustible mixture to the cylinders effected, and also a uniform heating of the mixture.

The invention will be more fully understood in conjunction with the description of the accompanying drawings; wherein—

Figure 1 represents in partial section an engine embodying the invention; Fig. 2 is a section taken on the line 2—2 of Fig. 1; Fig. 3 is a vertical section taken on the line 3—3 of Fig. 1; and Fig. 4 is a detailed section taken on the line 4—4 of Fig. 3.

In Fig. 1, is shown a block casting for four cylinders 1, 1, 1, 1, respectively, having their heads cast integrally and sur-

rounded by a water jacket casing 2 forming a water jacket 3 inclosing all of the cylinders, the valve chambers, the charge inlet manifold pipe and the exhaust pipe. 5 represents the exhaust pipe which extends longitudinally on one side of the casting, being partially surrounded by the water jacket and which is connected by pipes 6 within the water jacket to the various exhaust valve chambers 7, 7, 7, 7. The exhaust pipe 5 extends out through the rear end of the casting, as shown at 8, and will be connected with the muffler in the usual manner. The top of the casting is open and will be covered by a removable cover, not shown herein. 10 represents an inlet passage between the second and third cylinders, and connected by opposite passages 11 to the double inlet valve chambers 12. The passages 11 are consequently completely inclosed within the water jacket and thereby are always heated to a uniform temperature by the water in the jacket. 13 and 14 are parallel vertically disposed primary mixing passages formed in the casting on one side between two of the cylinders, and connecting to the passage 10, which leads to the inlet valves. At the bottom of the block casting, and adjacent the lower ends of mixing passages 13, 14 is formed a horizontal circular passage 16, in which the fuel nozzle or nozzles are disposed; the bolts 17 secure the float chamber and nozzle casting 18 of the carbureter to the block casting. As herein shown, this casting 18 is formed in one piece, having an air inlet 19 and carrying nozzles 20, 21, which are connected to the passage 22 leading from the float chamber 23. The remaining parts of the carbureter are not shown, being unnecessary to an understanding of the invention, though it will be seen that 24 is a valve seat and 25 a gasoline passage leading from the gasoline tank. At the upper end of the passages 13, 14 a second chamber, or auxiliary mixing chamber 35 is formed in the casting, in which is fitted a cylindrical throttle valve 26 having ports 27 opening into the charge space 10, ports 28, 29 controlling the passages 13, 14, respectively, and ports 30 for admitting an additional air supply through ports 31 formed in a bushing 32 attached to the casting as by screw-threads. It will be seen that the threaded bushing 32 holds in place 110

a sleeve 33 which carries ports corresponding to 28, 29 and 30. 34 is a lever for turning the throttle valve cylinder 26.

- In operation, the ports 27 regulate the 5 quantity of mixture supplied to the cylinders, and the ports 30 admit an additional quantity of air when high power and speed are required, over and above the air which normally passes through the choking port 10. It will be seen that a partial mixture 15 is first formed in the primary mixing chambers 13, 14, serving respectively as main and additional mixing passages, and that the mixture is completed in auxiliary chamber 19. It will be seen that a partial mixture 20 is first formed in the primary mixing chambers 13, 14, serving respectively as main and additional mixing passages, and that the mixture is completed in auxiliary chamber 19. It will be seen that a partial mixture 25 is first formed in the primary mixing chambers 13, 14, serving respectively as main and additional mixing passages, and that the mixture is completed in auxiliary chamber 19. It will be seen that a partial mixture 30 is first formed in the primary mixing chambers 13, 14, serving respectively as main and additional mixing passages, and that the mixture is completed in auxiliary chamber 19. It will be seen that a partial mixture 35 is first formed in the primary mixing chambers 13, 14, serving respectively as main and additional mixing passages, and that the mixture is completed in auxiliary chamber 19. It will be seen that a partial mixture 40 is first formed in the primary mixing chambers 13, 14, serving respectively as main and additional mixing passages, and that the mixture is completed in auxiliary chamber 19. It will be seen that a partial mixture 45 is first formed in the primary mixing chambers 13, 14, serving respectively as main and additional mixing passages, and that the mixture is completed in auxiliary chamber 19.

As the walls of the mixing passages 13, 14 form part of the body of the engine, these 20 walls are directly heated from the cylinders, and consequently the atomization of the liquid fuel in these passages 13 and 14 is performed under the best possible conditions without introducing hot air, and without 25 other means for heating. The passage 10 being contained in one casting with the cylinders and being surrounded by the circulating water of the water jackets, is also at practically the same temperature as the cylinders, consequently the combustible mixture 30 is in the best condition for use in the cylinders. Owing to the close proximity of the mixing chamber to the cylinders the inlet pipes 11, which branch from the passage 10, 35 are of minimum length, but equal on both sides, so that an equal supply of mixture to each cylinder is obtained.

So far as I am aware, it has not heretofore been proposed to form a mixing passage 40 having a fuel nozzle adjacent one end thereof as a part of the engine casting and to embody a mixing chamber within the same water jackets as the cylinders, and in closest proximity to the cylinders.

Having thus described my invention, I declare that what I claim as new and desire to 45 secure by Letters Patent is,—

1. The combination with a multiple cylinder casting, of a mixing passage between two 50 of said cylinders having its walls integral therewith, a fuel nozzle disposed within the outer walls of said casting and adjacent one end of said mixing passage, an auxiliary mixing chamber within said casting between 55 said cylinders, and passages from said mixing chamber communicating with the interiors of said cylinders and within the outer walls of said casting.

2. The combination with a multiple cylinder casting, of a mixing passage between two 60 of said cylinders having its walls integral with the casting, a fuel nozzle disposed adjacent one end of said mixing passage, an auxiliary mixing chamber at the end of said 65 passage and between said cylinders, pas-

sages from said chamber communicating with the interiors of said cylinders and within the outer walls of said casting, a throttle valve in said mixing passage, and a water jacket surrounding said cylinders and said 70 passages.

3. The combination in a multiple cylinder block casting, of inlet passages to the cylinders formed in said casting, a common mixing chamber between two of said cylinders, 75 a passage leading through said casting from the outside to said mixing chamber, a fuel nozzle in said passage, and means for supplying liquid fuel to said nozzle.

4. A multiple cylinder engine casting having an enlarged charge mixing chamber between two of the cylinders, inlet passages to the cylinders from said chamber, a vertical passage formed in the space between said cylinders and connected to said chamber, a fuel nozzle and air inlet at the lower end of said passage, and a throttle valve in said mixing chamber.

5. A multiple cylinder engine casting having an enlarged charge mixing chamber 90 between two of the cylinders, inlet passages to the cylinders from said chamber, a vertical passage formed in the space between said cylinders and connected to said chamber, a fuel nozzle and air inlet at the lower end of 95 said passage, a cylindrical throttle valve in said mixing chamber, and an auxiliary air inlet through said mixing chamber and throttle.

6. A multiple cylinder engine casting having an enlarged horizontal charge mixing chamber between two of the cylinders, inlet passages to the cylinders from said chamber, a vertical passage formed in the space between said cylinders and connected to said 100 chamber, a fuel nozzle and air inlet at the lower end of said passage, a throttle valve in said mixing chamber, and an integral water jacket inclosing said cylinders, said inlet 105 passages, and said mixing chamber.

7. A multiple cylinder engine casting having a charge mixing chamber between two of the cylinders, inlet passages to the cylinders from said chamber, a vertical passage formed in the space between said cylinders, 110 a fuel nozzle and air inlet at the lower end of said passage, a cylindrical throttle rotatably mounted in said mixing chamber, an auxiliary air inlet through said throttle, and an integral water jacket inclosing said 115 cylinders, said inlet passages and said mixing chamber.

8. A multiple cylinder engine casting having a charge mixing chamber between two of the cylinders, manifold inlet passages extending to the cylinders from said mixing chamber, a pair of vertical passages between said two cylinders and having integral walls, a cylindrical throttle controlling said 125 passages, an air inlet and fuel nozzles for 130

said passages, and a water jacket inclosing said cylinders, said manifold inlets and said mixing chamber.

9. A multiple cylinder engine casting having a charge mixing chamber between two of the cylinders, manifold inlet passages extending equally to the cylinders from said mixing chamber, a pair of vertical passages between said two cylinders and having integral walls, a throttle mounted in said mixing chamber controlling said passages, an air inlet and fuel nozzles for said passages, a water jacket inclosing said cylinders, said manifold inlets and said mixing chamber, and a common cylinder exhaust pipe within said water jacket.

10. The combination with a multiple cylinder casting, of a mixing chamber within said casting between two of said cylinders and having its walls integral therewith, passages from said chamber communicating with the interiors of said cylinders and within the outer walls of said casting, and an air inlet and fuel nozzle for supplying an atomized fuel mixture to said mixing chamber, said inlet and said nozzle being disposed within the outer walls of said casting.

11. The combination with a multiple cylinder casting, of a plurality of primary mixing passages, individual means for supplying atomized fuel mixture for said mixing passages, a common auxiliary mixing chamber communicating with said mixing passages and disposed between two of said cylinders, said mixing chamber being provided with an air inlet, and passages from said mixing chamber communicating with the interiors of said cylinders.

12. The combination with a combustion engine comprising a plurality of cylinders and passages communicating with the interiors of said cylinders, of a plurality of nozzles, individual primary mixing chambers for said nozzles, means for supplying fuel

to said nozzles, a common auxiliary mixing chamber provided with an air inlet, said common mixing chamber communicating with said individual mixing chambers severally and with said passages, and a valve for controlling the flow of the gas mixture from said common mixing chamber into said passages.

13. The combination with a combustion engine comprising a plurality of cylinders and passages communicating with the interiors of said cylinders, of a plurality of nozzles disposed side by side, individual primary mixing chambers for said nozzles, said primary mixing chambers being disposed in parallel relation and of varying internal capacity, means for supplying fuel to said nozzles, a common auxiliary mixing chamber provided with an air inlet, said common mixing chamber communicating with said individual mixing chambers severally and with said passages, and a valve for controlling the flow of the gas mixture from said common mixing chamber into said passages.

14. The combination with a multiple cylinder casting, of a mixing passage having portions of its walls integral with certain of said cylinders, a plurality of parallel chambers formed by walls cast integrally with said casting, said chambers serving as fuel mixing chambers, and a hollow element adapted to be inserted in an opening in the casting above said chambers, said element having openings in its walls adapted to register respectively with the ends of said chambers, whereby said hollow element serves as a common mixing chamber for said plurality of chambers.

In testimony whereof I affix my signature, in presence of two witnesses.
